UNITED STATES PATENT OFFICE.

GURDON S. MUMFORD, OF NEW YORK, N. Y.

APPARATUS FOR CONSTRUCTING CONCRETE WALLS.

1,122,983.

Specification of Letters Patent. Patented Dec. 29, 1914.

Application filed August 12, 1914. Serial No. 856,454.

To all whom it may concern:

Be it known that I, GURDON S. MUMFORD, a citizen of the United States of America, residing at New York, in the county of New

5 York and State of New York, have invented certain new and useful Improvements in Apparatus for Constructing Concrete Walls, of which the following is a specification.

10 This invention relates to an apparatus for constructing concrete walls and in its more intense aspect, to a device for holding certain parts of a molding apparatus in place during the process of casting.

15 In order that the present invention may be more clearly understood, it may be noted by way of explanation that in casting concrete walls, more particularly cellar and foundation walls, as well as the upper walls 20 of a building, it is customary to employ side molds extending either to the full height of the finished wall or sectional molds which are progressively raised in a step by step manner as the wall is cast. In using apparatus

25 of the latter character more particularly, some difficulty has been experienced in properly spacing and tying the lower edges of the sectional mold together to prevent lateral movement thereof in either direction during the actual pouring of the concrete and casting of the wall. Various devices have been employed, but they have been accompanied by certain objections that render them commercially impractical. For

30 example, should it be attempted to use a hollow sleeve surrounding a transverse tie bolt from which the bolt is withdrawn after the casting of the wall, there is always the danger that the hole left by the sleeve will 35 be improperly sealed; thereby leaving a transverse leak in the finished wall. If on the other hand, the sleeve should be omitted and a single transverse rod used, the outer ends of which were bolted or clamped to

40 the outer surface of the side mold members, these rods would have to be withdrawn on dismantling the mold which would leave a transverse opening accompanied by the same objection. Should it be attempted to 45 use a shorter transverse rod having threaded ends adapted to engage socket bolts passing through the side mold members to avoid this objection, there would occur the objection of expense in constructing a tie device 50 of this character as well as the absence of an efficient anchor.

The present invention is designed to overcome the above possible objections and to provide a simple and practical device which would be cheap to manufacture.

60

Another object is to provide a device of the above character which will be reliable and efficient in use.

A further object is to provide a device of the above character which will not only act 65 as a tie and spacing means for the mold members during the casting operation, but will also act as a reinforcement for the finished wall and permit a more rapid operation of the casting of the wall.

70

Other objects will be in part obvious and in part hereinafter pointed out.

The present invention accordingly consists in the features of construction, combination of elements and arrangement of 75 parts which will be exemplified in the device hereinafter described, and the scope of the application of which will be indicated in the following claims.

In the accompanying drawing, there is 80 shown in sectional elevation one of various possible embodiments of the present invention and while this invention will be hereinafter described in its application to an apparatus for casting a double wall, in a 85 step by step manner, it is understood that the tie means forming the subject of this invention is capable of various uses and applications and is not to be limited to its relation to a molding device of this or any 90 other particular character.

Referring to the drawing in detail, which is more or less diagrammatic, there is denoted at 5 and 6 a pair of coacting side mold members between which is positioned a 95 hollow core 7 for the purpose of casting a double or hollow concrete wall therebetween. These mold members are adapted to be progressively raised in the present instance after permitting the wall cast therebetween to have partially set. Suitable guides and framework (not shown) are, of course, provided for guiding and directing the movement of these mold members.

It has been found by experience that in 105 using mold members of relatively large size approximately twenty-five feet long by four feet high and each weighing several hundred pounds that it has been difficult to properly clamp or hold the lower edges especially of the side molds against lateral movement during the casting operation. A 110

tie member such as herein disclosed comprises a piece of wire 8 having each end wound into a helical coil 10 adapted to be engaged by a headed bolt 11 passing loosely 5 through an opening in the side mold and threaded at its inner end to engage the helical coil. The tie member 8 is preferably made of a single piece of relatively heavy steel wire in a stock size having a total 10 length substantially equal to a thickness of the finished wall and the angle 12 portion connecting the central portion or body of the wire with the coiled ends is preferably tempered or hardened to prevent any 15 stretching whatsoever of the tie during the positioning of the mold.

In use the mold members 5 and 6 are approximately positioned with respect to the plane of the finished wall, the tie members 8 20 inserted therebetween at desired intervals and one of the bolts 11 is passed through the opening in one side member and screwed into the helical end to its full depth thereby drawing the inner side of the mold snug 25 against the helical end of the tie. The other bolt 11 is then inserted in a similar manner in the opposite mold and tightened which draws the molds together and positively holds them against lateral movement in 30 either direction. If a core 7 were used as in casting a hollow wall, the core is preferably made in sectional form so as to fit between and closely adjacent the tie members being separated only by the diameter of the wire, 35 although if a complete mold and core were constructed as of boards the ties would be placed between the boards thereof when built. The wall is then cast by pouring semi-liquid concrete or cement between the 40 molds and core and after it has partially set, the bolts 11 are withdrawn and the side molds raised to cast the next layer. The tie member remains in the wall and by reason of its enlarged roughened or corrugated ends 45 acts as a reinforcement or anchor securely holding the partially set walls against lateral movement. In this manner, the wall may be cast much more rapidly than could be done if a straight tie were used for example, having a threaded end engaging a 50 socket bolt. The expense of such construction is clearly very small for the tie in the form herein shown may be made of plain wire in large quantities at a relatively small 55 expense and the bolts, side molds and core may be repeatedly used.

It is thus seen that the present invention provides a simple, practical and inexpensive

device which is reliable and efficient in use, adapted to accomplish among others all of 60 the objects and advantages above set forth.

As many changes could be made in the above construction and many apparently 65 widely different embodiments of the invention could be made, without departing from the scope thereof, it is intended that all matter contained in the above description or shown in the accompanying drawing shall be interpreted as illustrative and not in a 70 limiting sense.

I claim:

1. An improved tie member comprising a wire having a straight body portion and its ends continued in the same direction and bent into enlarged helices adapted to co-act 75 with threaded bolts and bear against the inner walls of mold members.

2. A tie member for concrete molds comprising a straight body portion having its ends bent into helices and lying in the same 80 line with the body portion, said helical ends being adapted to engage threaded bolts passing through mold members to draw the ends of the tie member into engagement with the inner faces of the mold.

3. A tie member for concrete molds comprising a single piece of relatively solid material adapted to be left in the finished wall and formed at each end with a helical anchoring device adapted to co-act with bolts 90 passing through the mold members to draw the anchoring devices into engagement with the inner faces of the mold members.

4. A tie member for concrete molds comprising a straight body portion having its 95 ends bent into helical anchoring devices adapted to receive threaded bolts passing through the mold members, said devices being hardened or tempered between the helical ends and the body portion.

5. A tie member for concrete molds comprising a straight body portion having its ends bent into helical anchoring devices adapted to receive threaded bolts passing through the mold members, said devices being hardened or tempered between the helical ends and the body portion, and said helical ends and body portion lying in substantially the same straight line.

In testimony whereof I affix my signature 110 in presence of two witnesses.

GURDON S. MUMFORD.
